UNITED STATES PATENT OFFICE

EDWARD C. MAURER, OF ST. PAUL, MINNESOTA

LAUNDRY SORTING MACHINE

Application filed August 9, 1929. Serial No. 384,626.

My invention relates to a sorting machine which may be adapted for use in laundries, to sort out the bundles, and is designed to carry the several bundles belonging to the same party and discharge the same into a container automatically. A feature of my sorting machine resides in its simplicity and also in the multiplicity of receiving compartments for the bundles. These receiving compartments are divided into two portions so that bundles may be dropped into either end of the same thus giving a double sorting capacity to my machine.

A feature of the invention resides in suitable automatic tripping means which are adapted to trip the keys which carry the bundles at the proper time and to automatically discharge the bundles into either end of the receiving compartments.

The invention further includes a sorter wherein an endless carrier is provided with a series of carriages adapted to receive a key member and which key is adapted to support a bundle and carry the same by the carriage and carrier means until the key reaches the proper position above a receiving receptacle and at which point the key is adapted to engage a trip lever to operate the same which releases the key and drops the bundle.

A further object of the invention resides in an operating lever to remove the key at the proper receptacle and to simultaneously trip a deflector which causes the bundle to drop either into one end or the other end of the receiving compartment for the bundles.

My sorting machine is particularly adapted for laundry use where it is desirable to drop all of the bundles for the same individual or parties into the same receiving receptacle. However, the machine is equally adaptable as a sorter for packages in the parcel post department of the mails where the bundles and packages are sorted out to be carried over a certain route. By my sorter these packages may be readily handled to deliver them automatically at a certain destination. Thus it is also apparent that my sorter may be equally adapted for use in the department stores where bundles are sorted out for certain routes particularly where these bun-

dles are of a comparatively equal size and not of a nature to prevent the bundles being carried from the shipping department to the delivery department where they are sorted out for the drivers of the different routes. 53 My sorter may be made sufficiently large or small to accomplish the variations to which it may be subjected or desired for use and it is particularly important to consider that I have designed my sorter of an extremely simple nature, requiring a small number of parts and adapted to operate to readily carry the bundles and discharge them automatically at a pre-determined point, depending upon the key which carries the bundle from its starting point and which automatically causes the bundle to be discharged at a pre-determined point or into a receptacle provided for the same. 60

My invention further includes a particular and peculiar key which is adapted to be employed and used in conjunction with the carriers to support the bundles. 70

All of these features and other objects will be more fully accentuated and pointed out 75 throughout the specification and claims.

In the drawings forming part of this specification:

Figure 1 is a plan view of my sorting machine which is particularly designed for use 30 in the handling of bundles in laundries, a portion of the same being broken away.

Figure 2 is a side view of Figure 1, a portion of the same being broken away.

Figure 3 is a detail of a portion of the 85 carrier, tripping levers, key and support of the shoulder in enlarged formation.

Figure 4 is a sectional edge view of the parts of Figure 3 in the opposite direction.

Figure 5 is an enlarged detail of the carriage off of the track and showing one of the tripping levers in the act of pushing the key off of the carriage, showing arrows to indicate the movement of the carriage, of the tripping arm and the key. 90

Figure 6 is a side view of one of the receiving receptacles and a portion of the shoulder deflector and operating levers therefor.

Figure 7 is a plan view of the shoulder receiving receptacle and the deflector therefor. 100

Figure 8 is an edge view of the key showing the straight formation thereof in full lines, and showing the dotted variations of the formations of the different keys.

5 Figure 9 diagrammatically illustrates an edge view of one shape of key.

Figure 10 is a diagrammatic edge view of another shape of the key.

10 Figure 11 is a diagrammatic edge view of another shape of the key.

15 My sorting machine A is formed with a continuous overhead track B formed by a suitable angle iron member 10 illustrated in cross section in Figure 4 which is adapted to be supported by suitable post members 11 and framework 12 at the top of the posts to support the track B.

20 An endless link belt 13 is operated over the sprockets 15 which are positioned on one end of the carrier and the sprockets 16 are adapted to carry the endless belt 13 over the other end of the machine A. The endless belt 13 operates adjacent the track B formed by the angle iron 10.

25 The sorter A is provided with any number of bundle carriages, such as C, illustrated in Figure 5 and also illustrated in Figures 3 and 4 which are attached in a suitable manner to the link belt 13 so that as the belt travels about the machine on the sprockets 15 and 16 the carriages C will be moved around on the track 10. Each carriage is provided with upper wheels 18 which ride upon the horizontal leg 19 of the angle 10 and with an idle roller 20 which bears against the vertical leg 21 of the angle iron track B. The frame of the carriage which supports the rollers 18 and the roller 20 is formed with upwardly projecting lugs 23 which slide along and may engage against the bar 24 so as to hold the carriage C on the track B with the rollers 18 bearing against the leg 19 of the track. This bar 24 extends about the machine and prevents the carriage C from running off of the track B.

40 Projecting from the frame of the carriage C I provide a key lug 25 which is formed with an annular recess 26 in which the key D is adapted to engage, when the key is hooked on to the carriage C. The keys D are formed of different shapes so as to be adapted to carry the bundles by the carrying pin 27 which may be in the form of a large safety pin or other suitable bundle engaging means and which is supported to the key by the link 28 so that 45 the bundles are carried by the keys D and the keys are made of such a shape as will be hereinafter more fully pointed out, to operate the tripping mechanism of the sorter so that the bundles may be carried about by the sorting machine to the proper receptacles provided.

50 Each key D is formed with an upper end which is formed with a hook and head portion 29 shaped so as to engage in the recess 26 of the lugs 25 and it will be noted that 55 the head 29 may either extend straight in line

with the body of the key D, as illustrated in the diagrammatic view of Figure 8, or may be bent in a manner to extend to either side of the body, as illustrated by the dotted outlines 30 and 31, a more or less degree to provide the variations for each of the keys D. This forms a simple key end 29 for each key and by increasing or decreasing the bend or offsetting of the hook head end 29 the keys D may be sufficiently varied so as to operate 70 the particular trip levers to which they are adjusted. In this manner these keys D form tripping means for operating the trip levers when the heads 29 of the respective keys come in contact with the lugs 32 projecting from the key members 33 of the respective tripping levers 34 and 35.

75 The levers 34 and 35 are positioned in pairs and near each other, being pivotally supported at 36 and 37, respectively. The lever 34 is provided with a weighted end 38 to normally hold the lever 34 against the stop pin 39 and with its adjustable key plate held by the nut 40 in the proper adjusted position on the free end of the lever 34 so that when one 90 of the bundle keys D passes along the track carried by the carriage C and which is formed to engage the lug of the key plate 33, the lever 34 will be operated as illustrated in the diagrammatic view in Figure 5, to push the bundle key D off of the supporting pin 26, permitting the bundle key with its bundle hook 27 to drop into the receptacle E below the same. The arrangement of the tripping levers 34 and 35 in pairs is such that they are supported above the bundle receiving receptacles E so that when the bundle is carried along to the proper receptacle E for which the key is set to operate the respective levers 34 and 35, the bundle key D will be tripped off and the bundle dropped off into the proper receptacle E.

95 The lever 35 is connected by the arm 42 to a depending rod 43 which is adapted to extend to each of the receptacles E, as illustrated in Figures 2 and 6, and which is connected to a slidable cross lever 44 which is adapted to operate the deflector 45. The deflector 45 is pivoted at 46 to the receptacle E 100 and by a short lever 47 the lever 44 is connected in such a manner as to operate the deflector 45 to move it from the full line position into the position illustrated in dotted outline in Figure 6. One end of the lever 44 is slidably connected at 48 and the lever 44 is flattened at 49 so that when the lever 35 is 105 operated by one of the keys D the movement of operating the deflector 45 starts in slowly owing to the movement of the lever 44 in a longitudinal direction and then increases with sufficient rapidity to throw the deflector 45 over into the position illustrated in dotted outline or toward the opposite side of the receptacle E. Thus when a bundle is 110 carried by its bundle key D and the key D 115

120

125

130

135

is formed to engage and operate one of the levers 35 the deflector 45 is thrown over so as to deflect the bundle dropping from the carriage C to the opposite side of the receptacle E.

Each receptacle E is provided with a deflector 45 and these deflectors are pivoted in the sides of the receptacle. A balance weight 50 is connected to the deflector as illustrated in Figures 6 and 7 so that the deflector 45 is always brought back to normal position after it has been operated by the lever 35. This provides a means of dropping bundles into either end of the receptacles E.

Thus my bundle sorter may operate to carry bundles from any starting point on the track B, and this track may be as long as desired and as many receptacles E as desired may be placed in connection with and associated with the sorting mechanism of the sorter A, so that all of the bundles for a particular person may be dropped at the same place or into the same receptacle and each receptacle may be adapted to receive two sets of bundles, one at either end. It is also evident that the sorter may be operated to carry packages and these packages will be sorted out automatically by the sorter A to drop all of the packages which are carried by the same formation of key at the same place, or into the same compartment or receptacle. The deflector 45 and its operating means simply divides the compartments or receptacles E so that they may be used for greater sorting in a smaller space and it is clearly evident that a large or smaller number of variations of keys may be employed with different shaped head portions 29 to be operated by the releasing key plates 33. It is also evident that the head portions 29 of the keys may be varied in height, permitting them to pass under certain of the key release plates 33 while they will be tripped by others which are set to engage a particular formation of key D.

The operation of my bundle and package sorter is quite simple, the endless belt may be driven by a motor M which operates the drive shaft 53 and in turn by means of the gears 54 one of the sprocket wheels 15 is driven to operate the endless link belt 13, thus moving the carriages C around on the track B continually in the operation of the sorter.

My sorter is adapted for use for laundries where numerous bundles are handled and where it is desirable to have several bundles for the same party. The sorter A saves considerable time and labor in the handling of a large number of bundles and packages and it is equally adaptable to parcel post use for sorting bundles out for the different routes as well as department stores, and in fact, any place where it is desirable to sort out a large number of bundles automatically. The operation is effective and the trip levers 34 and

35 are operated by the respective keys D to drop the packages at the points desired and into the compartments E. The entire operation is automatic requiring little or no attention and providing a sorting device which is adapted to handle a large number of packages or bundles in a very effective manner.

In accordance with the patent statutes I have described the principles of my sorting machine and I have endeavored to represent the best embodiment thereof, nevertheless various changes may be made and other adaptations applied within the scope of the following claims.

I claim:

1. A package sorting machine comprising, an overhead track, carriages adapted to be operated on said track, means for moving said carriages, tripping lever means arranged in pairs, receptacles beneath said tripping means and track, deflector means in each of said receptacles, a package key adapted to support a package to be carried by each of said carriages, and means for automatically tripping the package off of said carriage and simultaneously operating the deflector of the receptacle to cause packages to be discharged into either end of the receptacles.

2. A bundle sorter including, track means, carriage means adapted to carry a series of bundles, tripping means arranged in pairs, a receptacle for each pair of tripping means, keys adapted to engage said tripping means to operate the same, a portion of said tripping means operating to discharge a bundle into one end of the receptacle below, and another portion of said tripping means operating to discharge a bundle in the other end of said receptacle below.

3. A laundry bundle sorter including, a series of receptacles, a track arranged above said receptacles, pairs of tripping levers positioned above said receptacles associated with said track, carriages adapted to operate on said track, means for operating said carriages around said track, bundle carrying keys adapted to be operated off of said carriages by said pairs of tripping levers, one of said levers tripping a package into one end of the receptacle below and the other into the other end of the receptacle below.

4. A bundle sorter comprising, a series of receptacles carriage and track means arranged above said receptacles in a manner to carry bundles to be deposited into said receptacles, and pairs of tripping levers for each of said receptacles adapted to automatically trip the bundles in a manner to discharge some of said bundles in one end of said receptacles and some of said bundles in the other end of said receptacles.

5. A bundle key for a bundle sorting machine adapted to carry the bundle and to be tripped at a pre-determined point, said key including a flat plate-like body portion, and

70

75

85

90

105

110

115

120

125

130

a portion offset from the plane of said body portion, the variation of one key from another to change the tripping key being formed in the degree of offset from the plane of the plate and length of the head of said bundle key.

6. A bundle key including, a plate-like body portion, a hook formed in said key, a head portion adjacent said hook formation, link means for carrying a bundle on the end of said key opposite said head portion, and said key being formed with right or left offset portions offset from the plane of said plate to form variations from one key to the other.

15 7. A bundle key including, a plate-like body portion, a hook formed in said key, a head portion adjacent said hook formation, link means for carrying a bundle on the end of said key opposite said head portion, and said key being formed with right or left offset portions of different lengths offset from the plane of said plate.

20 8. An automatic bundle sorter for laundry including, a track means, an endless belt carrying means, carriages adapted to be operated by said endless belt means, a series of receptacles, each having a deflector, a pair of tripping levers, and bundle keys, one of said levers being adapted to operate to release the bundle key with its bundle in one end of the receptacle, and the other of said levers having means connected therewith to automatically operate said deflector in the receptacle at the moment of tripping the bundle key from the carriage.

25 9. A bundle sorter including, a series of carriages, a bundle key having a hook for engaging with said carriage to carry a bundle, a track for said carriage, belt means for operating said carriage on said track, tripping levers, receptacles below said tripping levers, said levers having adjustable tripping plates on the free end thereof, one of said levers being adapted to trip said bundle keys with the bundle in one end of the receptacle, and the other adapted to trip the bundle key to discharge the bundle in the other end of the receptacle.

EDWARD C. MAURER.
